UNITED STATES PATENT OFFICE.

ALBERT WANNER, JR., OF NEW YORK, N. Y.

MANUFACTURE OF CHAIR-SEATS.

1,251,715.

Specification of Letters Patent.

Patented Jan. 1, 1918.

Application filed November 19, 1915. Serial No. 62,344.

To all whom it may concern:

Be it known that I, ALBERT WANNER, Jr., a citizen of the United States, residing at New York city, in the county of New York 5 and State of New York, have invented certain new and useful Improvements in the Manufacture of Chair-Seats, of which the following is a specification.

This invention relates to chairs, for instance of the bent-wood class, whose seats are made with removable tops so as to permit the user to replace worn tops with new ones. My invention consists in a novel method of forming the removable tops of 15 chair seats whereby certain advantages in the step of incorporating the caning or other form of woven seat proper in such top as a part thereof are effected and whereby a seat top is produced which affords a perfectly plane surface on the under side and 20 may further be made considerably thinner than is possible by any known method.

In the accompanying drawings,

Figure 1 shows a continuous wood member in transverse section;

Fig. 2 is a similar view of said member after the caning constituting the woven seat proper has been applied thereto;

Figs. 3 and 4 show said member after the 30 further step of dividing the same in a horizontal plane has been effected, Fig. 3 being the lower and Fig. 4 the upper section or top thus produced;

Fig. 5 is a view corresponding to Fig. 2, 35 but illustrating a modification of the method;

Fig. 6 is a view corresponding to Fig. 4, but illustrating the top produced by the method illustrated by Fig. 5;

Figs. 7 and 8 are sectional views, on a 40 larger scale, of the seat tops shown in Figs. 4 and 6, respectively, forming parts of chair seats; and,

Fig. 9 is a plan of a chair seat having 45 one of such tops.

A suitable length of wood is first bent into the form of an endless member *a*, the ends thereof being secured together in any manner well known. Preferably, the piece 50 of wood has one transverse dimension greater than the other, and when the bending is performed it is that dimension which is parallel to the axis of bending. Said member has a continuous groove *b* or rout formed 55 in one of the plane surfaces thereof.

Next, having cut a piece *c* of flexible

sheet material which is to form the seat proper (such as already-woven or so-called "machine" caning or the like) to circular form, the diameter thereof being somewhat 60 greater than that of the groove or rout *b*, and having applied glue or other cement *d* preferably continuously in the groove, a binding strip *e*, such as a reed, is superimposed upon the marginal portion of the piece 65 *c* over and continuously of the groove and then jammed into the same, it being understood that the groove is preferably sufficiently narrow so that some compression of the marginal part of the caning *c* and the 70 strip *e* must take place before they will enter the groove, whereby when entered therein the friction set up will contribute toward stoutly maintaining the joint which will be formed after the cement sets. Of 75 course, the piece of caning *c* is subjected to considerable tension by this operation, wherefore until the cement sets the strip *e* is by some means, such as clamps, positively held in place.

Next, in a plane, as *f*, which is parallel with the plane surfaces of the member *a*, the latter is sawed or otherwise divided into two parts, *g* and *h* (Figs. 3 and 4), the part *h* thus produced being the product aimed 85 at by the present method.

The present method possesses the advantage that by joining the seat-proper *c* to the element that is to form its frame (to wit, the part of member *h* above the plane *f* in 90 Fig. 2) before such element is cut away from the part *g* of member *a*, the yielding and bending to which said part would be subject under the severe strain imposed thereon incident to the tension of the material *c* when it is bound in place by forcing the strip *e* into the groove *d* does not have to be prevented by special means, since the strength of the material of the piece *a* is sufficient of itself to resist such yielding and 95 bending.

Again, it will be noted that the under side of the frame of the part *h*, or seat top, thus produced will be perfectly flat or plane. In this connection it may be remarked that 105 it has heretofore been proposed to divide a continuous member, as *a*, in a plane between its plane surfaces, and then weave onto one of the sections thus produced as a frame, having first provided a continuous series of 110 holes therein for the purpose, a cane seat, but in that case, since the cane strands ex-

tended from hole to hole at the relatively under side of the frame, it was necessary either to groove the chair frame or ring on which such a seat top was to be superimposed to accommodate the strands or countersink the strands in the under side of the frame for the caning. According to my method since the seat proper *c* is not woven onto its frame, but is joined to the member *a* (in substantially the way described) already woven, the connection of the seat proper to its frame not depending on strands of the caning being passed in loops through such frame but only on the seat proper being at its margin entered somewhat into it, the seat top produced may be attached to any seat ring or frame of a chair without preliminary treatment of, as by grooving, either (see Fig. 7). A indicates the chair frame.

Moreover, the seat top produced, may be as thin as desired, so long as the plane of division does not extend through the caning. Attention is directed to Figs. 5, 6 and 8, where the plane of division *f* intercepts the

groove so that the frame of the seat top in effect comprises two concentric wooden sections *i* and *j* joined only by the glue or other cement *d* and the caning margin and strip *e* embedded in such cement.

The method herein described may, as indicated by the dotted lines at *k* and *l* in Fig. 3, be repeated with respect to the part *g* of member *h* which remains after the first seat top is produced until the whole of the material thereof is used up.

Having thus fully described my invention, what I claim as new and desire to secure by Letters Patent is:—

The method herein described consisting in forming a bent-wood endless member, attaching a piece of sheet material to one plane surface of said member continuously thereof and so that said piece will be held uniformly taut by said member, and finally dividing said member in a plane between its plane surfaces and close to but not through said piece of sheet material.

In testimony whereof I affix my signature.

ALBERT WANNER, Jr.
